UNITED STATES PATENT OFFICE.

WILLIAM O. GREER, OF KENTENIA, KENTUCKY.

PUMP SEPARATOR.

Application filed March 29, 1923. Serial No. 628,621.

To all whom it may concern:

Be it known that WILLIAM OWEN GREER, a citizen of the United States, residing at Kentenia, in the county of Harlan and State 5 of Kentucky, has invented certain new and useful Improvements in Pump Separators, of which the following is a specification.

This invention has reference to pump separator attachments for interposition between the intake and discharge to prevent dirt or grit or other impedimenta from reaching the operating parts of the pump.

The invention comprises a casing or chamber with necks having screw connections for attachment of a casing to the intake of the pump with interposed screen material acting as a sieve for removing dirt or the like from the water and delivering clean water to the operating parts of the pump while the casing is provided with a clean-out port permitting the removal of extracted material as needed.

In accordance with the invention, the casing is formed with separated necks for the attachment of couplings to the casing to direct the water as pumped through the sieve or screen to collect the extracted material in the casing and permit its removal from time to time through the port.

The invention will be best understood from a consideration of the following detail description taken in connection with the accompanying drawings forming a part of this specification with the understanding that the invention is not confined to any strict conformity with the showing of the drawings but may be changed and modified so long as such changes and modifications mark no material departure from the salient features of the invention as expressed in the appended claims.

In the drawings:

- Figure 1 is an elevation of the pump separator;
 45 Figure 2 is a section on the line 2—2 of Figure 1;
 Figure 3 is a section on the line 3—3 of Figure 2; and
 Figure 4 is a detail section.
 50 Referring to the drawings, there is shown

a casing 1 made in the form of a substantially rectangular casting with diametrically opposed necks 2 and 3 and another neck 4, all the necks terminating in flanges 5 and provided with interior screw-threads 6 for the attachment of pipe couplings for connecting pipe fittings thereto.

The casing 1 is provided intermediately with an interior inturned ledge 7 forming a seat for a diaphragm 8 of screen material fastened to the ledge 7 by means of screws 12 or other fastening devices. The screws 9 secure a plate 10 to the ledge 7 with an interposed packing gasket 11 while the screen material 8 is held in place by other screws 12 passing through a metal strip 13 clamping the screen 8 in position.

The necks 2 and 3 leading into the casing 1 are separated from another neck 14 leading to the working section of the pump so that the water entering the casing 1 by way of necks 2 and 3 will flow in the neck 14 after passing through the screen 8.

The neck 4 is provided with a removable screw cap 15 which may be removed at will to admit access to the interior of the casing 1 separated from the neck 14 by the screen 8 so as to permit the cleaning of the interior of the casing from accumulated sand or grit as needed.

The neck 4 constitutes a drain port for the removal of accumulated trash, coal, gravel, etc., to protect the valves of the pump, this being accomplished by the screen 8 directing the accumulated trash into the compartment 1 of the separator, thus saving time and trouble in cleaning and replacing obstructed valves.

The separator will be varied in size to fit different dimensions in suction lines and different conditions to be accommodated.

In the assembly the neck 14 is uppermost in the casing 1 and the neck 4 is lowermost so as to direct the waste accumulation due to the presence of a screen 8 to a local point.

What is claimed is:

A device of the class described comprising a casing, having a pair of inlets at opposite sides thereof, an outlet in one side of said casing, a flange formed in the casing, and ex-

tending inwardly from the opposite side between the inlet and the outlet, a vertically arranged screen element having its edges disposed against the flange, a U-shaped clamping strip positioned against the edges of the screen element, fastenings passing through the clamping strip and flange, the bottom

walls of the receptacle being inclined, a drain plug at the bottom of the casing, and a removable cover secured to the upper face of said casing. 10

In testimony whereof I affix my signature.

WILLIAM O. GREER.
